UNITED STATES PATENT OFFICE.

JOHN W. STEPHENSON AND DAVID C. STEPHENSON, OF TOLEDO, OHIO, ASSIGNORS TO THE NATIONAL MALLEABLE CASTINGS COMPANY, OF CLEVELAND, OHIO, A CORPORATION OF OHIO.

RAIL-ANCHOR.

1,031,969.

Specification of Letters Patent.

Patented July 9, 1912.

Application filed March 14, 1912. Serial No. 683,652.

To all whom it may concern:

Be it known that we, JOHN W. STEPHENSON and DAVID C. STEPHENSON, of Toledo, Lucas county, Ohio, have invented a new and useful Improvement in Rail-Anchors, of which the following is a specification, reference being had to the accompanying drawings, in which—

Figure 1 is a plan view of our invention; Fig. 2 is a section of the rail showing the rail anchor in position; Fig. 3 is an elevation of the rail flange showing the rail anchor; and Fig. 4 is a perspective of the key member shown in Figs. 1, 2 and 3.

Our invention relates to rail anchors and is designed to provide a simple, effective and positive means for anchoring the rail and to prevent it from creeping. The rail anchors or anti-creeping devices which have heretofore been provided for this purpose have not proven satisfactory in use for the reason that they work loose and become ineffective in service, or are so complicated that they cannot be correctly or readily applied to the rails by the ordinary track laborer. For efficient service it is of the greatest importance that a device of this character should be positive in its action, and should be secured to the rail without the possibility of its working loose from either the rail or the stationary element with which it cooperates to prevent movement. The anchor should also be of such character that it can readily and easily be applied to the rail by unskilled workmen. Such a device is provided by our invention.

Referring to the drawings, 2 designates a portion of the track rail; 3, 3' are the rail flanges; and 4 is the tie.

5 is the anchor having the projection 6 adapted for engagement with the flange 3' of the rail 2, and having depending webs 7 which lie below the rail base and are adapted to be attached to the tie 4 by the bolts, or similar fastening means, 8. At the side opposite the projection 6, the anchor 5 has an upwardly extending member 9 which has under-cut bearing surfaces 10, the base of which is inclined longitudinally and vertically with respect to the rail, and which, with the rail flange 3, form guideways 11 for the keys 12. The guideways 11 have restricted curved portions 13. The keys 12 are of wrought metal capable of bending

and have a driving heel 14 and a lip 15 for engagement with the rail flange.

After the anchor 5 has been placed in position and fastened to the tie 4 by the bolts 8, and with the rail flange 3' under the lip of the projection 6, the keys 12 are inserted and driven into the guideways 11, the inner end portions 16 of the keys 12 striking the curved wall 17 of the guideway portions 13, and are deflected therefrom laterally and outwardly, as is shown in Fig. 1. The keys 12 have inclined bearing faces 18 which contact with the bearing faces 10, which forces the lips 15 and the vertical face 19 on the opposite faces of the keys to grasp firmly the rail flange 3. The bending and deflection of the keys 12 in the curved portion of the guideways 11 forms a secure and clinching engagement which will prevent the key from working loose, so that the key will hold the anchor securely to the rail and prevent the rail from creeping by reason of the anchor 5 being firmly secured to the tie 4.

It will be seen that when the keys 12 are inserted and driven home, in the manner described, that they form secure and positive fastenings which cannot work loose, and the initial and proper application of the keys is secured, since the laborer has only to insert the keys and drive them in as far as they will go. If it becomes necessary at any time to remove the rail, this can be done by sledging the abutments 20, which are located on the upper surface of the keys 12, in the opposite direction from that in which the key was driven when originally inserted. This will force the bent ends of the keys out of the curved guideways and release the binding engagement of the anchor to the rail.

While we have shown a rail anchor having two bendable members, it is obvious that an efficient anchor can be obtained where only one bendable key member is provided.

Other changes may be made in our improved anchor without departing from our invention, since—

What we claim is:

1. A track anchor for rails, comprised of plates and a connecting web member for engagement of a tie, said plates and said web member having means for securing to said tie, said plates having upwardly extending projections, one of which projec-

tions is adapted to engage a flange of the rail, and the other of which has an undercut face inclined longitudinally of the rail and a bendable key member adapted to be driven in between said inclined undercut face and the other flange of the rail to bind the rail and the anchor firmly together.

2. A track anchor for rails, comprised of plates for engagement of the tie, one of said plates having a projection to engage a flange of the rail, and the other side of the plate having an upwardly extending member, a guideway between said upwardly extending member and the other flange of the rail, and a bendable key adapted to be driven into said guideway to secure said anchor to said rail, and a vertically dis-

posed web member connecting said plates adapted to be secured to the tie.

3. A track anchor for rails, comprised of a saddle for engagement of the tie, projections from said saddle, one of the projections from said saddle being adapted to engage a flange of the rail, another of said projections forming with the other flange of the rail a guideway, and a bendable key member adapted to be driven into said guideway to secure said saddle to said rail.

JOHN W. STEPHENSON.
DAVID C. STEPHENSON.
